(57) **CLAIM**

The ornamental design for a rain chain component as shown and described.

DESCRIPTION

FIG. 1 is an upper perspective view of a rain chain component;

FIG. 2 is a lower perspective view of the rain chain component;

FIG. 3 is a front elevational view of the rain chain component, the opposite side having the same configuration;

FIG. 4 is a right side elevational view of the rain chain component, the opposite side having the same configuration;

FIG. 5 is a top view of the rain chain component;

FIG. 6 is a bottom view of the rain chain component; and,

FIG. 7 is an upper perspective view of the rain chain component shown in the position of use, interconnected to multiple rain chain components to form a rain chain. The broken lines in FIG. 7 showing multiple rain chain components are environment only and form no part of the claimed design.
